(57) **CLAIM**

The ornamental design for a probe for a ultrasonic diagnosis apparatus, as shown and described.

DESCRIPTION

FIG. 1 is a perspective view 1 of a probe for an ultrasonic diagnosis apparatus showing my new design according to a first embodiment thereof,

FIG. 2 is a perspective view 2 thereof,

FIG. 3 is a front elevational view thereof,

FIG. 4 is a rear elevational view thereof,

FIG. 5 is a top plan view thereof,

FIG. 6 is a bottom plan view thereof,

FIG. 7 is a left side elevational view thereof,

FIG. 8 is a right side elevational view thereof,

FIG. 9 is a perspective view 1 of a probe for an ultrasonic diagnosis apparatus showing my new design according to a second embodiment thereof,

FIG. 10 is a perspective view 2 thereof,

FIG. 11 is a front elevational view thereof,

FIG. 12 is a rear elevational view thereof,

FIG. 13 is a top plan view thereof,

FIG. 14 is a bottom plan view thereof,

FIG. 15 is a left side elevational view thereof; and,

FIG. 16 is a right side elevational view thereof.

The broken lines in the drawings and the areas within them depict portions of the probe for an ultrasonic diagnosis apparatus that form no part of the claimed design.
